COMBINED FLASHLIGHT AND COMPASS

Lloyd E. Hawks, Ann Arbor, Mich.

Application March 18, 1939, Serial No. 262,690

3 Claims. (Cl. 240—6.4)

The present invention relates to a new and improved combined flashlight and compass.

An important object of the invention resides in the provision of a compass especially adapted for day or night use whereby the finding of true north is readily accomplished for determining a location or to march a course between two predetermined stations.

A further object of the invention resides in the provision of a housing mounted at right angles to the casing of a flashlight and having removably and rotatably mounted thereon an illuminated compass dial, said dial forming a part of a traversing head which is provided with a ratchet ring, suitably graduated with notches for engagement with a spring mounted in the lamp housing to provide an audible means for indicating the degree of rotation of the traversing head.

The invention will be fully and comprehensively understood from a consideration of the following detailed description when read in connection with the accompanying drawing which forms a part of the application.

In the drawing:

Figure 1 is a top plan view of a combined flashlight and compass embodying the features of the present invention.

Figure 2 is a fragmentary transverse sectional view thereof.

Figure 3 is a detail sectional view taken substantially on line 3—3 of Figure 2.

Figure 4 is a detail sectional view taken substantially on line 4—4 of Figure 1, and

Figure 5 is a side elevational view of the device.

Referring to the drawing for a more detailed description thereof, there is illustrated a flashlight 8 including a casing 9 and illuminating end 10 which end supports the conventional bulb lens and reflector. Current is supplied to the illuminating head by means of a plurality of dry cell batteries 11 disposed in series with the contact end 12 of the foremost battery electrically associated with the contact end of the bulb in the head 10 and controlled by a suitable switch generally designated by the reference numeral 13.

The illuminated compass extends at right angles to the casing 9 and includes a housing 14 integrally mounted at right angles to the casing, or welded or otherwise secured thereto. Within the housing 14 there is disposed a conductor plate 15 carrying a socket 16 for receiving a lamp bulb 17. The conductor plate 15 is suitably insulated as indicated at 18 from which projects a contacting element 19 having connection with the contacting end of the lamp bulb 17. Current is supplied to the contacting element 19 from the battery 11 by means of the conducting wire 20 which extends through suitable insulation 21 along the casing 9 and within the housing 14. A second contacting member 22 projects from the

conductor plate 15 adapted to be contacted by the slideable switch element 23 to complete the circuit for illuminating the bulb 17, said switch element 23 moving within a slot 24 formed in the casing 9 and actuated by means of a switch button 25. Thus it will be seen that the illuminating element carried by the housing 14 is operated independently of the illuminating head 10 but from the same source of electrical energy. In addition to illuminating the compass dial, the bulb 17 will also heat the needle compartment enough to prevent the needle bearing from sticking or freezing when using the device in cold weather.

The projecting end of the housing 14 is threaded as indicated at 26 for receiving the traversing head generally designated at 27. Within the housing 14 and adjacent the threaded portion 26 there is provided a clicking device in the form of a spring 28 having one end riveted or otherwise secured at 29 to the housing and the opposite end formed with a knob 30 projecting through the housing as more clearly shown in Figure 3 of the drawing and for a purpose to be herein-after described.

The traversing head 27 supports therein a translucent dial 31, one face thereof having engagement with the annular shoulder 32 formed on the head and being held thereagainst by means of an annular spring 33. The dial 31 is suitably graduated being preferably formed with 72 graduations each representing 5°. A needle 34 is journaled in suitable bearings 35 carried by the dial 31 and is equipped with a mechanical needle arrester 36 operated from the outer portion of the dial by means of the knurled disc 37, it being understood that rotation of the disc 37 brings the arrester 36 into and out of engagement with the needle 34 to arrest and permit motion of the same. A glass cover E is suitably mounted within the head 27 for protecting the dial and needle while maintaining said parts readily visible.

The traversing head 27 is formed with a threaded portion 38 for engagement with the threaded portion 26 of the housing 14 for retaining said head in position. As is to be understood the threaded portion 38 extends circumferentially of the head to permit said head to rotate on the housing. The traversing head 27 is also formed with a multiplicity of vertically disposed notches 39, preferably 72 in number, each notch representing 5°, to conform with the graduations of the dial 31. After the head has been positioned on the housing and rotated a certain distance thereon, the knob 30 of the spring member 28 will have engagement with said notches 39 to provide an audible clicking device. Continued rotation of the head will cause the knob 30 to successively engage each of the notches until the head has reached its

limit of rotation. During the fabrication of the traversing head the dial 31 is disposed in a manner whereby the north, east, south and west indicators are in line with corresponding deeper notches 40 formed in the traversing head, one of which is indicated in Figure 3 of the drawing. Thus in rotating and positioning the head on the housing, it will be a relatively simple matter to place the north and south indicators of the dial in line with the axis of the casing 9 and the east and west indicators of the dial at right angles to said casing since the notches for north, east, south and west are noticeably deeper than the other notches.

To march a course from, for example, station A to station B, the bearing of which is N 30° E, the procedure by day is as follows: The traversing head is first set with north and south indicators in line with the axis of the casing with the north pointing in a forward direction which position is easily found from the deep ratchet notch for north. The traversing head 27 is then rotated to the left or counter-clockwise 6 notches which sets off 30° and as the traversing head is rotated the clicking noise will indicate each individual notch of rotation. The compass needle is then released and the entire device is oriented until the indicator N is under the north pole of the needle at which time the axis of the casing points N 30° E and therefore toward station B.

To determine a course by day from, for example, station A to the next visible point, the flashlight tube is first pointed in the direction of the next point on the march. The compass needle is then released and the traversing head rotated until the indicator N is under the north pole of the needle and while rotating the head noting the number of 5° notches passed from north, east or west, or south, east or west for bearing of the line.

To march or determine a course by night, the switch 25 is first actuated to illuminate the compass dial 31 and the procedure is substantially the same as that described above with the beam of light denoting the marching direction and the bearing of any distant object within its range may be established in the manner above indicated.

It is to be understood that the illuminating head 10 and traversing head 27 are readily interchangeable whereby the forward end of the flashlight may be employed for supporting the compass and the housing 14 carrying the illumination for the direction of the travel.

The removable end 41 of the casing 9 is provided with a spring-like receptacle 42 for supporting a spare lamp bulb 43 to be used as a replacement for a burned out bulb in either the illuminating head or the traversing head.

It is also to be understood that the illuminating head 10 is to be provided with a clicking device substantially the same as the spring member 28 previously described with the removable head also formed with graduated notches.

If desired a clip B may be attached to the casing 9 for securely retaining the device in the user's pocket or for suspending the same from a belt or the like.

Also it will be understood, of course, by those skilled in the art that variations in the here-

inabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In combination with an electric flashlight having a casing adapted to receive a source of electrical energy and illuminating means carried on one end thereof, of a direction indicating means comprising a housing carried by said casing and extending at substantially right angles thereto, illuminating means within said housing, a traversing head mounted on said housing, said head including a compass indicating dial and needle adapted to be illuminated by said means, a spring-like member carried by said housing and having one end thereof projecting through said housing, and means comprising vertically disposed notches formed in said traversing head adapted to be contacted by said spring to provide an audible clicking device as said head is rotated on said housing when setting said compass.
- 15 2. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 20 3. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 25 4. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 30 5. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 35 6. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 40 7. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 45 8. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 50 9. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 55 10. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 60 11. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 65 12. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
- 70 13. In combination with an electric flashlight having a casing adapted to receive a source of electrical energy and illuminating means carried on one end thereof, of a direction indicating means comprising a housing integral with said casing and extending at substantially right angles thereto, illuminating and heating means within said housing, a rotatable head mounted on said housing, said head including a compass indicating dial and needle adapted to be illuminated by said means, said dial having graduations thereon, vertically disposed notches formed in said head in line with the graduations of said dial, certain of said notches being of greater depth to indicate certain points of said compass, and means carried by said casing and cooperating with said notches to provide an audible indicating means as said head is rotated.
